UNITED STATES PATENT OFFICE.

GEORGE F. SCHORLING, OF FRESNO, CALIFORNIA.

COOKING STOVE AND RANGE.

1,190,468.

Specification of Letters Patent.

Patented July 11, 1916.

Application filed October 23, 1913. Serial No. 796,850.

To all whom it may concern:

Be it known that I, GEORGE F. SCHORLING, a citizen of the United States, and a resident of Fresno, Fresno county, California, have 5 invented a new and useful Improvement in Cooking Stoves and Ranges, of which the following is a specification.

My invention relates to cooking stoves and ranges, and its purpose is to provide separate compartments for different temperatures, and to have a circular top which can be readily revolved to bring certain segments of such top over the heating compartment desired. To accomplish this purpose I 15 have constructed my stove as hereinafter described.

In the drawings which accompany this specification Figure 1 is a view of the stove looking toward the door of the warming 20 oven. Fig. 2 is a view of a part of the stove having parts cut away to show a sectional view thereof on a line *a* shown in Figs. 3 and 4. Fig. 3 is a view of the circular top. Fig. 4 is a view of the stove from above and 25 with the top removed.

A represents the outside shell of the stove, which I have preferably constructed in the form of a perpendicular tube, having a bottom *e* therein, and being supported by legs *b*.

30 *c* is the door to the warming oven *h*.
d is the flue, which is preferably located in the center of the top of the stove.

g is the fire box.

35 *f* is a vertical partition which separates the compartment holding the fire box *g* from the warming oven *h*.

j is a horizontal partition covering the top of the warming oven *h*, and forming an air chamber *k* between the top of the warming 40 oven and the top of the stove. Air chamber *k* is separated from the compartment containing the fire box by partitions *m'* and dampers *n* which are adapted, when dampers *n* are closed, to have the draft from the 45 fire box *g* to the flue *d* unobstructed except by an adjustable damper *y*.

y' is a damper rod which operates damper *y*.

Air chamber *k* is divided into two approximately equal compartments by a vertical partition *m''* for the purpose of permitting one side of the stove to be heated more intensely than the other.

50 *m* are partitions extending between the top *B* and horizontal partition *j*. They are

in the form of an arc having a common center with shell *A*.

o is the ash receptacle under the fire box and *p* is the door through which the ashes can be removed.

60 On the top of horizontal partition *j* I have constructed a chamber *q*, having at the top thereof an opening adapted to receive the stove pipe, or flue *d*. The walls of chamber *q* are constructed with an outside shoulder, which is adapted to carry the top *B*. Top *B* is constructed circular in form and is provided with a plurality of lids covering holes 1, 2, 3, 4 and 5, and an oven 7.

65 *s* is a bearing on the top and inside of tubular shell *A*, and is adapted to support the outer edge of circular top *B*. Bearings *r* and *s* can be constructed as ordinary sliding bearings, or roller or ball bearings. It will thus be seen that the top *B* can be rotated on the top of the stove so that either the oven 7 can be turned to rest directly over the fire box *g*, or over the air space *k*, thus 70 permitting the instantaneous regulation of the application of heat to articles being 75 cooked or baked on the stove, and by this construction the entire surface of the top of the stove can be used.

75 The oven 7 is constructed with double walls *u* and *v*, and the chamber formed between such walls *u* and *v* has openings so the heat and fire from the fire box can pass freely therein. To better accomplish this 80 object I have constructed an auxiliary flue *w* which connects the chamber formed by walls *u* and *v* to the flue *d* by means of a band or sleeve *z* which is neatly fitted around flue *d*, and is fastened to auxiliary flue *w*. I have cut an opening 8 in flue *d* at such a point that when the top *B* is turned 85 so the oven is directly over the fire box, auxiliary flue *w* is in direct line with said opening 8, and when top *B* is turned so the oven is not over the firebox, the auxiliary flue *w* is closed by being held with ring *z* 90 against the wall of flue *d*.

95 In my construction I prefer to have a common center for the tubular shell *A* and partitions *m*, and to have such partitions extend from partition *j* approximately to top 100 *B*. I have also constructed dampers *t* between chambers *k* and *q*. Dampers *t* are adjustable by means of damper rods *t'*. When it is desired to admit additional heat to air chamber *k*, the dampers *t* and *n* are opened 110

and damper *y* is closed, thus forcing the heat and fire from fire box *g* to pass through air chamber *k*.

5 *g'* are hot water pipes which may be placed in the stove.

It will be noted that when the upper oven is brought forward over the fire box, the dampers *n* and *y* may be closed, and the products of combustion will then pass up around the oven 7, and through the passage *w* to the flue.

What I claim as my invention and on which I desire Letters Patent is:

1. In a cooking stove the combination of 15 an upright tubular shell, a bottom to such shell, a rotatable top on such shell adapted to carry cooking vessels, upright partitions dividing a vertical portion of the interior of such shell into segments, a fire box in one of such segments, a covering over the top of the 20 segment not containing such fire box, forming an air chamber between such covering and the rotatable top, a flue from such covering through the center of such rotatable top, having openings communicating with such fire box segment and such air chamber, a 25 damper in the opening between such fire box segment and such flue adapted to permit the heated air and smoke to pass directly from such fire box to the flue when 30 such damper is open and to retard such passage when such damper is closed, partitions separating such air chamber from such fire box segment having dampers therein 35 adapted to regulate the passage of hot air from such fire box segment to such air chamber, a damper between such flue and such air chamber adapted to regulate the passage of hot air from such air chamber to such 40 flue and an oven having double walls spaced to form a heating chamber, such oven being disposed on said rotatable top, and having openings through such rotatable top, which 45 communicate with the heating chamber between the walls and a lead communicating between such heating chamber and the flue, all substantially as described.

2. In a cooking stove the combination of 50 an upright tubular shell, a bottom to such shell, a rotatable top on such shell, upright partitions dividing a vertical portion of the interior of such shell into segments, a fire box in one of such segments, a covering over

the top of the segment not containing such fire box, forming an air chamber between 55 such covering and the rotatable top, a flue from such covering through the center of such rotatable top communicating with such fire box segment and such air chamber, a damper in each of such openings, partitions 60 between such fire box segment and such air chamber extending from such flue a portion of the distance toward the wall of such shell and thence extending rearwardly in such air chamber, forming a passageway between 65 the wall of such shell and such partition from the segment holding the fire box to such air chamber, dampers within such passageway and an oven having double walls spaced to form a heating chamber between 70 them, disposed on the upper side of the rotatable top with openings through such rotatable top into the heating chamber, a circular main flue from such stove and in the center thereof, an opening in the wall of such 75 main flue, a collar rotatably disposed around such flue, an auxiliary flue connecting such collar and heating chamber constructed to have the hole in the main flue communicate with a hole in the heating chamber when the oven is over the fire box, and to cut off such communication when the oven is not over the fire box.

3. In a cooking stove the combination of 80 an upright shell having a bottom and a rotatable top thereon, partitions therein forming separate compartments, a fire box in one of such compartments, a circular flue attached to a nonrotatable portion of such stove and extending through the center of such rotatable top, a warming oven on such 85 rotatable top constructed with double walls, and having an inclosed air chamber between such double walls, a hole in the wall of such flue, a collar adapted to encircle such flue 90 and to turn thereon, a passage way between such inclosed air chamber and such collar arranged to register with such hole in the wall of the flue at some point within range 95 of the movement of such rotatable top, all 100 substantially as described.

GEORGE F. SCHORLING.
